UNITED STATES PATENT OFFICE.

WALDO F. FOLLETT, OF NEW HAVEN, CONNECTICUT, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,101,068.

Specification of Letters Patent. Patented June 23, 1914.

Continuation of applications Serial No 600,495, filed January 3, 1911, and of Serial No. 684,995, filed March 20, 1912. This application filed October 8, 1913, Serial No. 793,998.

To all whom it may concern:

Be it known that I, WALDO F. FOLLETT, a citizen of the United States, residing at New Haven, in the county of New Haven and 5 State of Connecticut, have invented certain new and useful Improvements in Railway-Traffic-Controlling Apparatus, of which the following is a specification.

My invention relates to railway traffic controlling apparatus and particularly to that 10 class of apparatus in which railway traffic controlling devices located along the track-way are controlled from a central controlling mechanism usually termed an "interlocking machine." Such apparatus is generally known in the art as an "electric interlocking system."

The present application is a continuation 15 of my copending applications filed January 3, 1911, Serial No. 600,495, and March 20, 1912, Serial No. 684,995.

I will describe certain forms of apparatus and circuits embodying my invention, and will then point out the novel features there- 20 of in claims.

In the accompanying drawings, Figure 1 is a diagrammatic view showing one form and arrangement of apparatus and circuits for the control and operation of a railway switch and embodying my invention. Fig. 2 is a diagrammatic view showing a modification of the apparatus and circuits shown in Fig. 1 and embodying my invention. Fig. 3 is a view showing apparatus and cir- 25 cuits similar to those shown in Fig. 2 but applied to the control of the two switches of a crossover.

Similar reference characters refer to similar parts in each of the several views.

Referring first to Fig. 1, *c* designates a 30 railway switch which is operated by a switch mechanism *C*. The mechanism *C* comprises an electric motor to which operating current is supplied from power mains *X*, *Y* which are connected with a battery 70. The 35 supply of operating current to the motor is controlled by a relay device *R*, located preferably adjacent the switch; which relay device is controlled by a manually operable 40 circuit controlling lever *E* through the medium of control wires 9 and 14. The lever *E* is usually one of a plurality of similar levers comprised in an "interlocking machine."

The switch mechanism *C* may be of any 55 suitable type. In the form here shown, an electric motor *F* operates through suitable gearing a bar 4 adapted to reciprocate. This bar 4 carries a stud 5 which engages an "alligator crank" 6, which latter is connected with the rails of switch *c* by a rod 6^a. Fixed to the bar 4 are two dogs 10 and 11 which operate respectively two rocking circuit controllers 12 and 13 in a well-known manner, and a rod 7 connected with the 60 switch rails operates a circuit controller 8 for the purposes hereinafter explained.

The circuit controlling lever *E* comprises a shaft 15 carrying disks 2 of insulating material on which are contact bands 16, 57, 58 70 and 59 of conducting material, which bands are adapted to engage with contact fingers 17, 17^a, etc., for the control of the electrical circuits. This shaft 15 may be oscillated by means of a handle 18, and its oscillations 75 are controlled by indication devices *K^N* and *K^P* which are operated by magnets 22 and 21 respectively.

The relay device *R* comprises a field 23^a on which is a field winding 23, and an armature 80 24 which is adapted to oscillate through a small arc of a circle. Operatively connected with the armature 24 are contacts 26 and 27 which are adapted to control the 85 circuits of motor *F* as hereinafter explained. The winding of armature 24 is constantly 90 connected with the power mains *X*, *Y*, through wire 42, resistance *H²*, wires 43 and 44, hence this winding is constantly energized in one direction. The field winding 95 23 is provided with a circuit which is energized from the power mains *X*, *Y* and is controlled by contact bands 16, 16^a etc., on lever *E*. This circuit is closed when the 100 lever *E* occupies either extreme position of its stroke; for example, when the lever is in the position in which it is shown in the drawing, the circuit for field winding 23 is from positive power main *X* through wire 28, contact 17, contact band 16, contact 17^a, wire 36, winding of relay 32, wire 9, resistance *H'*, field winding 23, wire 14, winding of relay 33, wire 31, contact 17^b, band 16^b, contact 17^a, to negative power main *Y*. The resistance of this circuit is such that 105 relays 32 and 33 are not closed.

The operation of the apparatus shown in Fig. 1 is as follows: In order to reverse the

position of the switch rails *c*, the shaft 15 of circuit controller E is swung toward the right, that is, in the direction indicated by the arrow on the handle 18; until stopped by the indication latch 21^a engaging the dog 19^a of segment 19. The direction of current through field winding 23 is then reversed, the circuit for this winding then being as follows: from positive main X through wires 28 and 29, contact 17^b, contact band 16^a, contact 17^c, wires 30 and 31, relay 33, wire 14, field winding 23, resistance H', wire 9, relay 32, wires 36 and 38, contact 17^e, contact band 16^c, contact 17^f, wire 39 to negative main Y. It will be seen, therefore, that the contact bands 16, etc., and the contacts 17, etc., constitute a pole changer for reversing the connection of field winding 23 with the power mains X and Y. Owing to the resistance H', the resistance of relays 32 and 33, and the resistance of the field winding 23, the current which flows in the circuit just traced is insufficient to close the armatures 40 and 41 of relays 32 and 33. The field 23 is now energized with current in the proper direction to cause the armature 24 to swing in the direction indicated by the arrow, thereby shifting contact bars 26 and 27 to close the opposite set of contacts. An operating circuit is then closed through the windings of motor F as follows: from positive main X through wires 42 and 45, circuit controller 12, wire 46, contact bar 27, wire 47, field winding *f* of motor F, wire 50, contact bar 27, wires 48 and 49, armature winding *f'* of motor F, wires 90 and 44 to negative main Y. The motor F then operates to move bar 4 in the direction indicated by the arrow, thereby reversing the position of the switch rails *c*. Before the movement of the switch rails begins, the circuit controller 13 is rocked into its opposite position by dog 11, but this has no effect on the circuits now under consideration. After the movement of the switch is completed, circuit controller 12 is rocked by dog 10 to its opposite position, thereby opening the motor operating circuit between wires 45 and 46. Circuit controller 8 is reversed by the movement of the switch rails, so that at the completion of this movement a circuit is closed from wire 14 through wire 51, circuit controller 8, wire 52, circuit controller 12, wire 53, contact bar 26, wires 53 and 54, contact 17^h, contact band 57, contact 17^k, resistance H to negative main Y. This branch of the circuit forms a shunt or multiple circuit around the field winding 23, resistance H', and relay 32 of the hereinbefore described circuit and the current which now passes through the two multiple circuits is sufficient to cause 33 to close its armature 41. Armature 41 then closes a branch from wire 37 through armature 41, wire 55, contact 17^p, contact band

59, contact 17^r, wire 56, magnet 21, wire 60 to negative main Y. Magnet 21 is then energized to raise its latch 21^a out of the path of the dog 19^a on segment 19, thereby permitting the stroke of shaft 15 to be completed, releasing the locking mechanism in the usual manner. This last-mentioned portion of the movement of shaft 15 opens the "indication" circuits at contact bands 57 and 59 so that relay 33 opens, but it does not open the circuit of field winding 23 at contact bands 16, etc.

A movement of the switch rails *c* in the opposite direction would be accomplished in a similar manner, the current then passing from the power mains through control wires 9 and 14 and the field winding 23 in the reverse direction, and thereby changing the position of contact bars 26 and 27 to cause the motor F to rotate in the reverse direction. In this case, relay 32 would be energized upon the completion of the movement of the switch rails, allowing indication magnet 22 to raise the latch 22^a from the path of the dog 20^a on segment 20.

Referring now to Fig. 2, the switch operating mechanism C here shown comprises a screw 115 operatively connected with the armature *f'* of motor F, which screw co-operates with a longitudinally movable nut 116. This nut is rigidly connected with a plate 118 provided with a cam slot 120 which co-acts with a roller 117, which latter drives a bar 119 connected with the rails of switch *c*. The plate 118 carries two cams 130 and 131 which actuate circuit controllers 132 and 133 for purposes herein-after explained. The circuit controlling lever E', shown in Fig. 2, is of a usual and well-known type comprising a shaft 91 which is adapted to be oscillated manually and which operates contact members 121 to 126 inclusive. The movements of this shaft are as usual governed by return indication devices K^N and K^R, which devices are operated by magnets 22 and 21 respectively. Each of these magnets is provided with a separate indication circuit, the circuit for magnet 22 being controlled by circuit controller 132 and that for magnet 21 by circuit controller 133. One or the other of these circuit controllers is closed after the switch *c* has completed its movement in one direction or the other and has been locked; and the indication device corresponding to that position of the switch is thereby energized to permit the controlling lever to complete its oscillation and to lock or unlock other levers of the interlocking machine. The circuit controllers 125 and 126 serve to control the circuits of indication magnets 21 and 22. These controllers are not moved during the first portion of the movement of the shaft 91 up to the point at which it is stopped by the dogs 19^a or 20^a, but during

the remainder of the movement of the shaft is energized by this current and raises its armature, thereby moving latch 21^a out of the path of dog 19^a, and the lever E' may then be moved to the end of its stroke. During this latter portion of the movement of lever E', contact 125 is reversed and thereby opens the circuit of magnet 21 at this contact. A movement of switch c from its reverse position to the normal position shown in Fig. 2 would be similar to that just described. For such movement, the direction of the control current through field winding 23 of relay R is reversed by contacts 121 and 122, and contact bars 26 and 27 are thereby moved to the position shown in the drawing. A motor operating circuit is then closed through motor F from positive power main X through wires 138 and 144, contact 26, wire 146, motor armature f', wire 145, contact 27, wire 157, contact 132, wires 158 and 150, field f, wires 151, and 139, to negative power main Y. This current is in the proper direction to cause the motor to move the switch to its normal position. When this movement has been completed and the switch rails have been locked by the longitudinal portion of the cam slot 120, circuit controller 132 is moved to the position shown in the drawing, thereby closing the following indication circuit through magnet 22 of normal indication device K^r—from positive power main X, through wires 138, 162 and 159, contact 132, wire 160, contact 126, wire 161, magnet 22, wire 156 to negative power main Y. The control lever is then permitted to complete its movement thereby opening the indication circuit just traced at contact 126.

It will be noted that in the form of my invention shown in Fig. 2, as well as in the form shown in Fig. 1, the circuit for the field winding 23 of relay R is closed when the control lever E' occupies either extreme position of its stroke. This is an important feature of my invention.

67 is a relay which may be employed to control any desired circuit or circuits. The circuit for this relay includes the two indication wires 154 and 160, and branch wires 68 and 69 connected respectively with the indication wires 154 and 160. The branch wires 68 and 69 include respectively contacts 123 and 124 one of which is closed only when the lever E' is in one extreme position of its stroke and the other of which is closed only when the lever is in the other extreme position of its stroke. It will be seen, therefore, that the relay 67 is energized only when the switch c and the control lever E' are in corresponding positions and when each occupies an extreme position of its movement.

Referring now to Fig. 3, I here show a "cross-over" comprising two switches d and d', both of which are controlled by the manual lever E'. Each switch d and d' is oper-

100

130

ated by a motor F through the medium of an operating mechanism C' exactly as the switch e in Fig. 3. The two motors F, F, are each provided with an operating circuit 5 each of which circuits is controlled by a relay R as in Fig. 2. It is well understood that when the two switches of a cross-over are controlled by a single lever it is essential that the return indication should be given 10 only when both switches have moved and have been locked in response to a movement of the controlling lever. In the arrangement of apparatus and circuits here shown, each indication circuit includes two circuit 15 controllers in series, one of which is operated by one switch mechanism and the other by the other switch mechanism. In this manner I insure that both switches have moved to the position corresponding to the position 20 of the controlling lever before the indication circuit for that position can be closed. As shown in Fig. 3 both of the switches d and d' are in their normal positions. When it is desired to reverse these switches, lever 25 E' is moved in the direction indicated by the arrow until it is stopped by the engagement of dog 19^a of indication device K^a with latch 21^a. This reverses the current through winding 23 of relay R and this relay is thereby 30 actuated to reverse the position of contact members 26 and 27. Current is then supplied to the operating circuits of the motors F, F. The operating circuit for motor F of switch d is from positive power main X 35 through wires 190 and 162, contact 26, wire 163, motor armature f', wires 164 and 165, contact 27, wire 166, contact 133, wires 167 and 168, motor field f, wires 169 and 170 to negative power main Y. The operating circuit 40 for the motor of switch d' is from positive power main X through wires 190, 162 and 171, contact 26, wires 172 and 173, motor armature f', wire 174, contact 27, wire 175, contact 133, wires 176 and 177, motor field f, 45 wires 178 and 170 to negative power main Y. When the movements of both switches have been completed and the switches have been locked, circuit controllers 133 of both switch mechanisms are reversed in position thereby 50 opening the motor circuits just traced and closing the reverse indication circuit which is as follows: from positive power main X, through wires 190, 162 and 179, contact 133 for switch d, wires 180, 181 and 182, contact 55 133 for switch d', wire 154, contact 125, wire 155, reverse indication magnet 21, wire 156 to negative power main Y. Magnet 21 being energized by this circuit, the stroke of lever E' can be completed, thereby opening the 60 indication circuit just traced at contact 125. A movement of the two switches in the opposite direction, that is to their normal positions, is similar to that just traced and therefore need not be explained herein in 65 detail. The relay 67 is controlled in the

same manner as in Fig. 2, hence no further explanation is necessary.

Although I have herein shown and described only a few forms and arrangements of apparatus and circuits embodying my invention, it is understood that various changes and modifications may be made therein within the scope of the appended claims without departing from the spirit and scope of my invention.

Having thus described my invention, what I claim is:

1. In combination with a traffic controlling device; means for operating said device from one position to another comprising an electric motor; a source of operating current; a relay comprising a field coil and an armature coil; contacts moved by the relay for controlling the supply of operating current to the electric motor to cause reverse operations of the electric motor; a circuit including one coil of the relay and constantly energized from the source of operating current; a control lever; contacts operated thereby; and a circuit for the other coil of the relay controlled by said contacts and energized from said source of operating current when the control lever is in either extreme position; which control lever when operated in reverse directions moves its contacts to cause reversals of current in the circuit including them, whereby reverse operations of the relay and consequently the electric motor are obtained.

2. In combination with a traffic controlling device; means for operating said device from one position to another comprising an electric motor; a source of operating current; a relay comprising a field coil and an armature coil; contacts moved by the relay for controlling the supply of operating current to the electric motor to cause reverse operations of the electric motor; a circuit including one coil of the relay and constantly energized from the source of operating current; a control lever; contacts operated thereby; a circuit for the other coil of the relay controlled by said contacts and energized from said source of operating current when the control lever occupies either extreme position, which control lever when operated in reverse directions moves its contacts to cause reversals of current in the circuit including them, whereby reverse operations of the relay and consequently the electric motor are obtained; and an indication means for said device; an indication circuit therefor also supplied from the source of operating current; and contacts in said indication circuit moved by the control lever and by the means operating the traffic controlling device.

3. In combination, a single set of power mains; a source of current for constantly supplying current thereto; a traffic control-

ling device including an electric motor; an operating circuit extending from said mains to said motor; a current reversing switch controlling said operating circuit; a relay for operating the current reversing switch; a circuit for said relay independent of the operating circuit; and constantly supplied with current from the power mains; a control lever; contacts operated thereby for causing reversals of current flow in the relay circuit; an indication device for controlling partial movements of said control lever and comprising a magnet; and a circuit for said magnet which is independent of the operating circuit and supplied with current from the power mains.

4. In combination, a railway traffic controlling device, means for operating said device in reverse directions comprising an electric motor; a source of current, a relay for controlling the supply of current from said source to the motor to cause reverse operations of the motor; a control lever, contacts operated by the lever, and a circuit for the relay controlled by said contacts and including said source, which circuit is closed when the control lever is in either extreme position, which lever when moved in reverse directions moves its contacts to cause reversals of current in the relay circuit, whereby reverse operations of the relay and thereby of the electric motor and traffic controlling device are accomplished.

5. In combination a traffic controlling device, means for operating said device in reverse directions comprising an electric motor, power mains, a source of current supplied therefor, an operating circuit for said motor supplied with current from said mains, a relay for said device comprising a field coil and an armature coil and contacts for controlling the supply of operating current to the electric motor to cause reverse operations of the electric motor, a circuit including one coil of the relay and constantly energized from the power mains, a control lever for said device located at a distance therefrom, contacts operated by said lever, a circuit for the other coil of the relay which circuit is controlled by said contacts and is energized from said power mains, when the lever is in either extreme position, said control lever adapted when operated in reverse directions to move its contacts to cause reversals of current in the circuit including them, whereby reverse operations of the relay and consequently of the electric motor and traffic controlling device are accomplished.

6. In combination, a railway traffic controlling device, means for said device for operating it in reverse directions comprising an electric motor; power mains, a source of current supply for said mains, a relay for

said device for controlling the supply of current from said mains to the motor to cause reverse operations of the motor, a control lever for said relay located at a distance from the relay, contacts operated by said lever, a circuit for said relay including the power mains and controlled by the said lever contacts, which circuit is closed when the lever occupies either of its extreme positions, said control lever being adapted when moved in reverse directions to move its contacts to cause reversals of current in the relay whereby reverse operations of the relay and of the motor and traffic controlling device are accomplished.

7. In combination, a railway traffic controlling device, means for moving said device, a circuit for the control of said means, a circuit controller for the control of said circuit, a relay included in said circuit, the resistance of the circuit being normally such that the relay is not closed, means controlled by the traffic controlling device for reducing the resistance of the circuit under predetermined conditions whereby the relay will then close, and means controlled by the relay for governing the movement of the circuit controller.

8. In combination, a railway switch, means for moving the switch, a circuit for the control of said means, a circuit controller for the control of said circuit and having two control positions corresponding to the two positions of the switch, two locking devices for the circuit controller, one for preventing complete movement of the controller to each position until the switch has moved to the corresponding position, two relays included in the said circuit one for the control of each locking device, the resistance of the circuit being normally such that the current is insufficient to energize the relays, two low resistance shunts for the said circuit, one around each relay and a portion of the resistance of the circuit, a circuit controller in each shunt one or the other of which is closed when the switch is in one extreme position or the other whereby the current is then sufficient to energize the relay which is not then shunted.

9. In combination, a railway switch, apparatus for moving the switch, a circuit for the control of said apparatus, a circuit controller for the control of the circuit and having two control positions corresponding to the two positions of the switch, locking means one for each position of the controller for governing the movement of the circuit controller to the two said positions, two relays included in the said circuit, one for the control of the locking means for each position of the circuit controller, the resistance of the circuit being normally such that the current is not sufficient to energize the relays, and means controlled by the switch

moving apparatus when in its two extreme positions for increasing the current through that one of said relays corresponding to such position whereby such relay will be energized to actuate the locking means corresponding to the position of the switch.

10. In combination, a railway traffic controlling device, means for moving the device, a circuit for the control of said means, 10 a circuit controller for the control of said circuit, locking means for preventing complete movement of the circuit controller until the traffic controlling device has moved to the position corresponding to the position 15 of the circuit controller, relays one for each position of the device for the control of said locking means and included in the said circuit, the resistance of the circuit being normally such that the current is insufficient 20 to energize the relays, and means operatively connected with the traffic controlling device and acting when said device has moved to the position corresponding to the position of the circuit controller to affect the 25 circuit to increase the current in the relay corresponding to such position whereby the locking means is then actuated to release the circuit controller.

11. In combination, a railway traffic controlling device, means for moving said device, a circuit for the control of said means, 30 a circuit controller for the control of said circuit, a relay included in said circuit for governing the movement of the circuit controller, the current which flows in the circuit being normally insufficient to energize the said relay, and means operatively connected with the traffic controlling device for affecting the circuit to increase the current 35 flowing therein when the said device has moved to a predetermined position whereby the relay will then be energized.

12. In combination, a railway traffic controlling device, means for operating said device in reverse directions comprising an electric motor; a source of current, a relay for 45 controlling the supply of current from said

source to the motor to cause reverse operations of the motor; a control lever, contacts operated by the lever, and a control circuit 50 for the relay controlled by said contacts and including the said source, which circuit is closed when the control lever is in either extreme position, which lever when operated in reverse directions moves the contacts to 55 cause reversals of current in the relay circuit, whereby reverse operations of the relay and thereby of the electric motor and traffic controlling device are accomplished, an indication device for controlling partial 60 movements of said control lever and comprising an electromagnet, a circuit for said electromagnet independent of the said operating circuit and control circuit, and contacts operated by the traffic controlling device and by the control lever for controlling 65 said electromagnet circuit.

13. In combination, a railway traffic controlling device, means for operating said device comprising an electric motor, a source of 70 current, a relay comprising two coils, said relay comprising contacts for controlling the supply of current to the said motor from said source to cause reverse operations of the motor, means for energizing one of said 75 relay coils from said source in only one direction, a control lever, contacts operated thereby, a circuit for the other relay coil controlled by said contacts and energized from said source of current when the lever 80 is in either extreme position, which control lever when operated in reverse directions moves its contacts to cause reversals of current in the last-mentioned relay coil, whereby reverse operations of the relay and therefore of the electric motor and traffic controlling device are accomplished. 85

In testimony whereof I affix my signature in presence of two witnesses.

WALDO F. FOLLETT.
